UNITED STATES PATENT OFFICE.

GEORGE H. BLISS, OF PITTSFIELD, MASSACHUSETTS.

TELEPHONE SIGNAL APPARATUS.

SPECIFICATION forming part of Letters Patent No. 241,914, dated May 24, 1881.

Application filed November 29, 1880. (Model.)

To all whom it may concern:

Be it known that I, GEO. H. BLISS, of Pittsfield, county of Berkshire, and State of Massachusetts, have invented a new and useful Improvement in Telephone Signal Apparatus, of which the following description, in connection with the accompanying drawings, is a specification.

My invention relates to telephone-signals, and is intended as an improvement in the signal invented by me for which Letters Patent No. 223,469, dated January 13, 1880, and No. 225,327, March 9, 1880, were granted, to which reference may be had. In the said applications a series of clock-works were described as arranged to run synchronously, and each controls a signal-bell in the circuit, allowing it to sound only at a certain predetermined period of time, the said period being different at each instrument, so that only one bell can be sounded at a time, and the periods recur at regular intervals—as, for example, once a minute. In the latter of the said patents the bell-hammer is mechanically held inoperative and the coils of its magnet shunted, except at the period devoted to that particular instrument for operating its signal. There was also shown in the said patents an automatic stop mechanism to stop all the clock-works when they arrived at a definite point, the said stop remaining in position for a short interval, during which any slow-running clocks would catch up and be stopped, so that when allowed to start again by the disengagement of the stop all the said clocks would be in exact unison.

In the present embodiment of my invention the clocks are all automatically stopped at the end of the interval in which each has had its individual period for operation, and they remain so stopped until it is desired to signal one of the stations again, when the instruments are all started again simultaneously by electro-magnets removing the stop from engagement with the clock-work.

The electro-magnets for starting the clock-works, and which may be called the "starting-magnets," are independent of those that operate the signals; and the invention consists, partly, in the combination, with the clock-works and starting-magnets, of switches automatically operated by the said clock-works to

close a shunt around the said starting-magnets immediately after the said clock-works have started, and to keep the said shunt closed during the entire interval in which the period for signaling at each instrument occurs, thereby removing the resistance of the said starting-magnets from the circuit when used for signaling, the said switches breaking the shunts just before or at the moment that the clock-works are stopped, so that thereafter any current will be compelled to pass through the said magnets.

That portion of the devices and circuits which is operatively connected with the starting apparatus will be hereinafter distinguished by the word "starting" from that portion connected with the signaling apparatus proper, which will be qualified by the word "signaling" or "signal."

The signals, which may be operated by magneto-electric currents in the usual manner, are placed in the main circuit, and shunt-circuits are provided, which cut out the said magnets, the said shunt-circuits being controlled by the clock-works, to thereby control the operation of the signals. In my present invention circuit-breakers are placed in these shunt-circuits, and are operated by cams placed preferably on an arbor that makes one complete revolution in the interval that the clock-work is running, between the moment that it is started and that at which it is automatically stopped. This arbor may be called the "main arbor," and also operates the mechanism by which the clock-work is stopped. The cams for breaking the shunts are placed at different angular positions on the said main shaft in the different instruments, each being of proper shape to retain the shunt broken during a certain period in which the signal at that station may be sounded, after which the cam disengages the said circuit-closer, allowing it to close the shunt, and the controlling-cam in another instrument opens its shunt and retains it open for a certain period, during which any electric currents that may be thrown upon the circuit will have to pass through the signal-operating magnet and cause it to sound the signal.

In the central-office instrument, and in the others if desired, a pointer is placed on the main shaft and rotates therewith over a dial,

which is divided to correspond with the cam-surfaces in the different instruments, so that while the said pointer is passing through division 1 of the said dial the cam in the instrument of the first station is holding the short circuit open, all the others being closed, and while it is in division 2 the shunt at the second station is open, and so on. Thus the operator, by watching the pointer, will know at what time each signal can be sounded, and by throwing on or generating electric currents at the proper time, as when the pointer is in a certain division, the currents will be caused to pass through and operate the signaling-magnet at the station corresponding to the said division, and it will be seen that only the resistance of the particular signaling-magnet in operation is interposed in the circuit at any one time, and that while the instruments are stopped all the signaling-magnets are short-circuited, as there are no signal-shunts open in this position of the main arbor.

The invention further consists in details of construction and combination of the mechanical portions of the apparatus, as will be hereinafter fully described.

Figure 1 is a front view of a signal apparatus embodying my invention, the parts being in their normal position with the clock-work stopped, and the front portion of the enclosing-case and the dial being removed; Fig. 2, a detail of the main shaft and mechanism co-operating therewith in the position assumed shortly after the period of operation of the signal has begun; Fig. 3, a front view of the dial and pointer of the instrument in the same position as in Fig. 2; Fig. 4, a side elevation of a portion of the clock-work shown in Figs. 1 and 2, and Fig. 5 a diagram showing the arrangement of circuits and the relation of the signal-cams on the main shaft in a series of signals.

The clock-works are shown as driven by a mainspring, *a*, connected with and actuating a train of wheel-work, *b* *b'* *b''*, &c., which may be and is shown as the same as that of an ordinary clock, and terminates in an escapement, shown as governed by a balance, *c*, on a shaft, *d*, to regulate the movement of the train in the usual manner, the rate being substantially uniform in all the instruments that are to control the signals of a given circuit.

The shaft *e* of the wheel *b* has upon it the main cams which control the stopping mechanism of the clock, as well as the circuits by which the electric currents are made to pass through the starting and signaling magnets, or are shunted around the said magnets. This shaft preferably revolves in about a minute, as this interval is usually sufficient to allow a proper period for the signaling of all the signals on a circuit, each in its turn, and is provided with a stop-controlling disk, *f*, which operates on a projection, 2, of the stop-lever *g*, pivoted at 3, and adapted, when in the proper position, (see dotted lines, Fig. 3,) to engage the stop-cam *h* on the balance-shaft *d*, and

thereby arrest the movement of the clock-work. The specific construction of this stopping mechanism is not herein broadly claimed, as it will form the subject of a future application.

In order to operate the stop-lever *g* to stop the clock-work, its controlling-disk *f* is provided with a notch, 4, to receive the projection 2 of the said lever, and allow it to turn on its pivot and fall into engagement with the stop-cam *h*, the said notch and cam being so placed with relation to the time of movement of their respective shafts that the lever is allowed to turn just when the balance is completing its oscillation in the direction of the arrow, and falls against the shoulder 5 of the cam *h* and stops the train when the full force of the hairspring is acting on the balance, so that the moment the stop-lever is disengaged therefrom the balance begins its oscillation and the train starts with certainty. The lever is disengaged from the cam *h* to thus allow the train to start by an electro-magnet, *i*, the armature of which is provided with a long finger, *j*, the end whereof passes in front of an arm, *k*, extended from the lever *g*, so that when the said starting-magnet attracts its armature the finger *j* thereof strikes the arm *k* and tilts the lever *g*, disengaging it from the cam *h*, and at the same time raising the projection 2 from the notch 4. The rear face of the notch 4 is inclined, as shown, and in a single oscillation of the balance *c* the disk *f* is moved so far that the said inclined side of the notch 4, in engaging the projection 2, will hold the lever *g* disengaged from the shoulder 5 of the cam *h*, so that a single momentary impulse is sufficient to cause the clock-work to start, after which the controlling-disk *f*, or the rear side of the notch thereof, will prevent the stop-lever from again stopping the train until the notch comes around again in the rotation of the disk *f*.

The armature of the magnet *i* has a retractor consisting of a fine spring-wire, *l*, bearing laterally against the finger *j*.

The main-line circuit, in which all the signals are situated, is connected where it enters the station with the binding-screw 10, whence it passes by wire 15 to the magnet *i*, from the coils of which the circuit is continued by wire 16 to the binding-screw 11, whence it passes through the signal-operating mechanism to be hereinafter described, and thence to the binding-screw 10 of the signal-controlling mechanism, such as shown in Fig. 1, at the next station, or, if at the last station, it passes to ground to complete the circuit.

Branch wires 17 18, connected with the wires 15 16, respectively on either side of the coils of the magnet *i*, are joined the former to the pin *m* and the latter to the spring *n*, both supported on a block, *o*, of insulating material, the said spring pressing against the said pin and forming electrical contact therewith, except when positively raised therefrom by the lifting-toe *p* on the main arbor *e*. The said toe *p* is so placed relative to the notch 4 of the stop-controlling disk *f* in all the instruments that it

raises the spring n from the pin m just before the trains are stopped by the lever g , and retains it thus raised and the branch or shunt circuit between the wires 17 18 broken until 5 just after the trains are started, when the toe p at once passes the end of the spring n and allows it to fall into contact with the pin m . By this arrangement, when the clocks are stopped all the electric currents passing over 10 the main circuit between the screws 10 11 are obliged to pass through the magnets i , to thus cause the said magnets to attract their armatures and start the train, as before described; but after the said trains are started the shunt 15 circuits through the wires 17 18 are closed, thereby cutting out the resistance of the magnets i , which thus does not have to be overcome by the currents which operate the signals proper.

20 The signal-bells, which may be of any usual construction, are shown at s in Fig. 5 as of the well-known kind, containing a light polarized armature adapted to be vibrated under the action of the rapidly-reversed currents generated by an ordinary magneto-electric machine; but it is obvious that the said signals might be either single-tap bells or vibrators, or the operating-magnets shown might be merely relays to close a local signal-operating circuit.

25 In either case the electro-magnet r , operating or directly controlling the signal s , is placed in the main circuit between the starting-magnet of one controlling-instrument and that of the next, as shown in Fig. 5, and branch wires 30 21 22 pass from either side of the said signal-magnet r to the binding-screws 12 13 of the controlling-instrument, where the said branch wires 21 22 are continued by wires 23 24 to the pin t and spring u , forming a second circuit-breaker similar to the one m n previously described, and mounted beside it on the same insulating-block o . This circuit-breaker normally remains closed, thus completing the branch or shunt circuit 21 22 23 24 around the 35 signal-magnets r , (see Fig. 5), so that owing to the greater resistance of the said magnets the greater portion of the currents pass through the said shunts, and the signals are consequently not operated by the currents which operate the starting-magnets to start the trains, nor by any currents, except when the said branch or shunt is broken, which never takes place in but one at a time, owing to the difference in position of the cams v . When the trains 40 are thus started the circuit-breakers t u in the different controlling-instruments are each opened, one after the other, by the signal-controlling cams v on the main arbors e , and these cams are properly shaped to retain the said 45 circuit-breakers open for a sufficient period to allow the corresponding signal to be operated.

In Fig. 5 the signaling-cams v and circuit-breaker t u are shown separately from the toes p and circuit-breakers m n for the sake of additional clearness, the shaft e being indicated twice at each instrument, and the circuits and magnets are shown in full at two of the sta-

tions, while at the rest of the stations only the circuit-breakers t u and their operating-cams v are shown, as all the other parts are the same 50 at all the stations.

It will be seen that the cams v are so placed on the main arbors e relative to the stopping and starting point of the said arbors governed by the notched controlling-disks that when the 75 said arbors are all started simultaneously and rotate isochronously first one engages the end of the corresponding spring and raises it from engagement with the pin t , breaking the shunt around and causing the circuit to pass only 80 through the corresponding signal-magnet r , and then when the said cam has passed the spring u , and allowed it to drop and close the said shunt, the cam at the next instrument engages its spring u , and after it has passed the one at 85 the next instrument operates similarly, and so on for as many stations as there may be, a certain portion of the isochronous rotation of the said main arbors being devoted to the operation of each cam v , and no two of them operating at 90 the same time to open their respective shunts.

The main arbors e are provided with pointers w , (see Fig. 3,) which, as the said arbors rotate, pass over a dial, x , which is divided into spaces marked 1 2 3, &c., which correspond to 95 the position of the cams v at the different stations, so that while the said pointer is passing through the space marked 1 the cam v at station 1 is holding the circuit-breaker t u open, and while passing through the space 2 the circuit-breaker t u at station 2 is open, and so on.

At the right hand of Fig. 1 a starting-arm, y , is shown pivoted at 7, and provided with a flexible finger, 8, which, as the said arm is rocked on its pivot by the operator depressing 105 the end thereof which extends out through the case, comes in engagement with the side of the balance c and sets it into oscillation, the function of the said arm being merely to start the clock when it is stopped with the balance in a 110 middle position of its oscillation, as when the clock is run down.

The operation is as follows: The instruments are normally all stopped, as indicated in Figs. 1 and 5, the levers g engaging the shoulders 5 115 of the stop-cams h and the toes p holding the springs n disconnected from the pins m . The cams v are then at different distances from the ends of the springs u and the pointers w are at the zero-point, or vertical. Supposing, for 120 example, it is desired to signal station 4, the operator sends a current over the circuit, which passes through all the starting-magnets i and causes them to attract their armatures, and by the connected fingers j to throw the levers g 125 off from the shoulders 5 of the cams h , allowing all the clock-works to start simultaneously. As the pointer w passes through the space 1 the signaling-shunt 21 22 23 24 at the first station is broken by the cam v engaging the 130 spring u , and as the said pointer passes to space 2 the signaling-shunt at station 1 is closed and at station 2 is broken, and a similar operation takes place as the pointer passes

into the spaces 3 and 4. While the pointer is passing through space 4, and the signal-shunt at station 4 is consequently broken, the operator sends to line electric currents of the proper kind to operate the signals 5, being in this instance the short reversed currents generated by a magneto-machine, and the said currents, in passing over the line, will follow the shunts 17 m n 18 around the starting-magnet *i*, the 5 said shunts being closed when the clock-works first start, as hereinbefore described, and at all the stations except station 4 the said currents will also pass through the shunts 21 23 10 n t 24 22 about the signaling-magnets *r*, which 15 will consequently not be operated thereby; but at station 4 the currents will be obliged to pass through the coils of and operate the signaling-magnet *r*, since the signaling-shunt is broken at this point by the cam *v*, as shown in Fig. 2. 20 The operator may continue to send the currents and operate the signal at station 4 as long as the pointer *w* is passing over the space 4 and the cam *v* at station 4 is holding up the spring *u*; but the moment that it arrives at the 25 end of the said space the said currents must cease, as after this moment they would operate the signal at station 5 instead of that at station 4.

If desired, the disks *f* may be provided with two or more notches arranged at uniform intervals about its periphery, and the dials marked to correspond—as, for example, if there were only four stations on the circuit the said disk might have two notches 4 directly opposite one another, and the figures 5 6 7 8 of the dial be 30 replaced by the figures 1 2 3 4.

If desired, a second notch 4 might be placed close to the notch shown, so as to stop the pointer just before it arrives at the zero-point, such position of the pointer indicating that the 35 line is not in use, and when the subscribers have finished their communication the signals will be started again and immediately stop with the pointer at the zero-point, the projections 2 of the levers *g* then falling into the notch we have first described.

I claim—

1. In an individual signal apparatus, a series of instruments, each consisting of a clock-work adapted to control the operation of the corre-

sponding signal, and an automatic stop mechanism to stop the said clock-work at a definite point, combined with a starting-magnet to operate the said stop mechanism and allow the clock-work to start simultaneously with those of the other instruments of the series, 55 and a shunt or short circuit around the said starting-magnet and circuit-breaker therein, controlled by the said clock-work, whereby the said shunt-circuit is broken when the said clock-work is stopped and closed when the clock-work is in motion, substantially as and for the purpose described.

2. A clock-work having an oscillating balance and an inclosing-case therefor, combined with a starting-arm extended outside the said case, and provided with a flexible finger or wiper to engage the said balance and set it in oscillation when it has stopped in an intermediate position in its oscillatory movement, substantially as described.

3. The combination of the notched controlling-disk, the stop-lever, and its projection controlled thereby, and the balance and balance-shaft of the time-train and stop-cam thereon, arranged and to operate substantially as described.

4. A series of signaling-instruments each consisting of a clock-work or time-train, the automatic stop mechanism therefor, and the starting and signaling magnets in a single circuit, combined with independent shunts around the said magnets and circuit-closers therein operated by the said clock-work, all arranged as described, whereby, when the clocks are stopped, the signal-magnet shunts are all closed 85 and the currents confined to the starting-magnets, and when the clock-works are in motion the starting-magnet shunts are closed and the signal-magnet shunts in the different instruments are opened one at a time in succession, 90 as and for the purpose set forth.

In testimony whereof I have signed my name to this specification in the presence of two subscribing witnesses.

GEORGE H. BLISS.
